UNITED STATES PATENT OFFICE.

WILLIAM WILSON LEE, OF NORTHAMPTON, MASSACHUSETTS.

CARVING-FORK.

SPECIFICATION forming part of Letters Patent No. 393,510, dated November 27, 1888.

Application filed April 16, 1888. Serial No. 270,726. (Model.)

To all whom it may concern:

Be it known that I, WILLIAM WILSON LEE, of Northampton, in the county of Hampshire and State of Massachusetts, have invented a new and useful Improvement in Carving-Forks, of which the following is a specification, reference being had to the accompanying drawings, in which—

Figure 1 is a plan of my new fork with the guard removed. Fig. 2 is a cross-section of my new fork with the guard in place at line 2 2 of Fig. 1. Fig. 3 is a longitudinal central section of a guard provided with forked extension. Fig. 4 is a cross-sectional view of one form of guard. Fig. 5 is a modification.

My invention is a combined carving-fork and guard of novel construction, as hereinafter described, the object of my invention being to produce a combined carving-fork and guard which is cheaper and more durable than the combined carving-forks and guards heretofore made.

In the drawings, A is the shank, and B the guard, of the fork. The back of shank A has a recess, a, in the bottom of which is secured a post, a', having a hole, a'', through it near its outer or free end to receive the pin b, by which guard B is secured to the post a'.

A spring, a³, lying in recess a, and preferably supporting a washer, a', as shown, serves to keep the guard either closed or open, as re-

quired, by its upward pressure against the base of the guard, the guard being loosely pinned to post a', so as to be opened or closed, as desired. By this construction guard B is 35 very rigidly and firmly connected to the shank, and this is a matter of practical importance, as will be readily understood.

It is very desirable that the inner end of the guard should have flat bearing-surfaces a⁵ on 40 each side of the post a' for the spring a³ (or its washer a') to bear against in order to keep the guard very firmly and rigidly in its open position, as will be readily understood by those skilled in the art.

Guard B is shown with a forked extension, B', which serves as a rest, and this is the preferred form of construction; but of course the guard may be made without the forked extension, if desired. (See Fig. 5.)

What I claim is—

In a carving-fork, shank A, the back of which has a recess, a, in which is a stationary post, a', and a spring, a³, in combination with guard B, having bearing-surfaces a⁵ pinned to post 55 a', substantially as and for the purpose set forth.

WILLIAM WILSON LEE.
